UNITED STATES PATENT OFFICE.

JAMES LAYDEN, OF BROOKLYN, NEW YORK.

NECKBAND AND COLLAR HOLDER.

1,427,746.

Specification of Letters Patent. Patented Aug. 29, 1922.

Application filed May 14, 1921. Serial No. 469,515.

To all whom it may concern:

Be it known that I, JAMES LAYDEN, a citizen of the United States, residing at Brooklyn, in the county of Kings and State 5 of New York, have invented new and useful Improvements in Neckband and Collar Holders, of which the following is a specification.

This invention relates to the class of apparel and more particularly to neck bands and collar holders, an object of the invention being to provide an improved means for holding the neck band of a shirt and collar together without overlapping the 15 edges of either of these articles whereby to render the meeting edges of the collar and neck band flush and presenting a smooth flat surface both inside and outside of the neck band and collar.

20 Another object of the invention is to provide a structure of this character in which the neck band will fit in a flat manner against the circumference of the neck, eliminating any circumferential bulge or bulges 25 of the apparel against the neck caused by buttons and overlapping neck band and collar edges.

A still further object of the invention is to provide a structure of this character in 30 which the collar can be quickly applied to and removed from the neck band.

Another object of the invention is to provide a device of this character which will entirely eliminate the necessity of providing 35 buttons upon soft collars and the customary pins and holding bars for holding the front flaps of the collars in position.

In the drawings:—

Figure 1, is an edge view of the collar 40 holder.

Figure 2, is a perspective view thereof.

Figure 3 is a perspective view showing the 45 holder applied to the neck band of a shirt, and

Figure 4, is a view similar to Figure 3 showing the partial application of the collar to the neck band.

In carrying the invention into practice, 50 use is made of a neck band 10, the same comprising inner and outer folds 11 and 12, so that the ends of the band are open to permit access to be gained to the space between said inner and outer folds for a purpose to be hereinafter explained. The inner fold 11 at the end A of the neck band is

extended as at 13 beyond the vertical edge 14 of the outer fold 12 at said end A. The outer fold 12 of the end B is extended at 15 to the vertical edge 16 of the inner fold 11 at said end B so that when the neck band is 60 drawn together or completely closed around the neck of the wearer, the extensions 13 and 15 overlap. This provides a smooth circumference entirely around the neck band which adapts itself comfortably to the neck 65 of the wearer.

The extension 15 of the end B is provided with a hole 17 and at the end A of the neck band, the outer fold 12 is provided with a hole 18.

70 The holder for maintaining a closed condition of the neck band comprises an articulate member 19 which can be in the form of a celluloid or aluminum plate, is provided with ends C and C adapted to be extended 75 between the inner and outer folds of the neck band at the ends A and B respectively. This member is provided with companion tongues 20 and 21 which are exposed with respect to the ends A and B so that they may be passed 80 through the aforesaid holes 17 and 18 respectively, as shown in Figures 3 and 4. The tongues are pressed outwardly from the body 85 of the member 19 and their free ends are preferably curved in an opposite direction to provide guiding terminals 21 for a purpose to be hereinafter explained.

It will be observed that when the holder 90 is applied to the neck band as shown in Figure 3 it is entirely concealed between the folds of the neck band, except for the tongues 20 and 21 which are exposed from the front of the neck band. In applying the holder to the neck band one of the ends C is inserted into one end of the band and it is then manipulated so as to cause one 95 of its tongues 20 to engage in its mating opening of the band. When this is accomplished the other end of the holder is accordingly inserted in the other end of the 100 band.

The collar 22 is provided with inner and outer folds 23 and 24 which are so formed that the vertical fold comes snugly together 105 at the joint of the neck band. The holes 26 and 27 are formed in the inner fold 23 and the same are adapted to be engaged with the tongues 20 and 21 respectively. The outer fold 24 is provided on its underside with loops 28 and 29 which are disposed 110

with respect to the holes 26 and 27 so that said loops can be guided under the curved terminals 21 of the tongues 20 and 21 when the collar is fully closed. This serves to retain the outer folds closed together so as to present a neat and dressy appearance.

It will be understood from the foregoing that the entire circumference of the neck band and collar present a perfectly flat condition around the neck of the wearer, giving great comfort to the wearer in use of the invention. It will also be observed that the neck band when combined with a collar of the type described and co-acting holder 15 will permit the collar to be quickly and conveniently applied to or removed from the neck band as the occasion necessitates.

The arrangement further provides a means whereby no bulky obstructions are formed in the circumference of the collar which would retard movement of the scarf between the folds of the collar when tying the scarf.

In regard to the holder 19, I wish to be understood that while I have stated that the same is formed of celluloid, the same may

be constructed of any suitable well known material that may be found most appropriate for the occasion. For instance, aluminum, hard rubber or the like can be used 30 without departing from the spirit of the appended claims.

What is claimed as new is:—

1. A neck band closing means and collar holder comprising a plate having ends 35 adapted for extension between the folds of a neck band adjacent to the ends of said band, and tongues carried by said plate and pressed outward therefrom, said tongues extending toward each other and arranged on 40 the same horizontal line, as and for the purpose set forth.

2. A collar holder comprising an arcuate plate having ends adapted to be inserted between the folds of a neck band at the ends 45 of said band, and intermediate tongues struck up from said plate, said tongues extending in opposite directions and having their terminals spaced apart.

In testimony whereof I have affixed my 50 signature.

JAMES LAYDEN.
